UNITED STATES PATENT OFFICE.

LEON RUBAY, OF CLEVELAND, OHIO, ASSIGNOR TO THE WHITE COMPANY, OF CLEVELAND, OHIO, A CORPORATION OF OHIO.

DESIGN FOR AN AUTOMOBILE-HEADLIGHT.

48,396.

Specification for Design.

Patented Jan. 4, 1916.

Application filed September 4, 1915. Serial No. 49,124. Term of patent 7 years.

To all whom it may concern:

Be it known that I, LEON RUBAY, a citizen of the Republic of France, residing at Cleveland, in the county of Cuyahoga and State of Ohio, have invented a new, original, and ornamental Design for Automobile-Headlights, of which the following is a specification, reference being had to the accompanying drawings, forming a part thereof.

In said drawings, Figure 1 is a front ele-

vation of an automobile headlight showing my design, and Fig. 2 is a side elevation thereof.

I claim:

The ornamental design for an automobile headlight, as shown.

LEON RUBAY.
